UNITED STATES PATENT OFFICE.

ALFRED A. HULL, OF KNOXVILLE, TENNESSEE, ASSIGNEE TO DRAPER CORPORATION, OF HOPEDALE, MASSACHUSETTS, A CORPORATION OF MAINE.

THREAD-CUTTING TEMPLE FOR LOOMS.

Application filed January 3, 1924. Serial No. 684,144.

To all whom it may concern:

Be it known that I, ALFRED A. HULL, a citizen of the United States, and resident of Knoxville, county of Knox, State of Tennessee, have invented an Improvement in Thread-Cutting Temples for Looms, of which the following description, in connection with the accompanying drawing, is a specification, like characters on the drawing representing like parts.

This invention relates to improvements in thread cutting temples for looms and the object of the invention is to provide a simple and improved means whereby the movable blade shall be forced into engagement with the stationary blade during the cutting stroke thereby to secure an effective shearing action upon the thread or filling end.

A further object of the invention is to provide a construction in which a separate spring member is provided for thus forcing the movable cutter blade into engagement with the stationary blade and in which means are provided for adjusting the tension of the spring so as to secure the desired results under all conditions.

These and other objects and features of the invention will appear more fully from the accompanying description and drawings and will be particularly pointed out in the claims.

In the drawings:

Fig. 1 is a side elevation of a temple embodying a preferred form of the invention;

Fig. 2 is an end elevation of the construction shown in Fig. 1;

Figs. 3, 4 and 5 are views on an enlarged scale in perspective with a portion of the temple head shown in dotted lines and with the cutter member and associated parts particularly involved in this invention shown in different positions.

The general construction and purpose of a temple and a temple thread cutter for looms is so well known to those familiar with the weaving art that it is unnecessary to set the same forth in anything more than a general way.

The construction herein illustrated, except for those features involving the present invention, is substantially the same as that disclosed in the patent to Edward S. Stimpson, No. 1,366,084, January 18, 1921.

In this construction the bar 1 of the

usual temple has formed thereon and secured thereto the temple head comprising the pod 2, the cap 3 with the enclosed toothed roll 4 journaled on the studs 5 and the entire bar and head move forwardly when the lay strikes the depending heel 6.

The cutting mechanism of the temple comprises a vertical stationary cutter member shown as a flat steel blade 7 mounted at one side of a vertical recess 8 in the temple head. Near its upper end this blade is provided with a notch 9. A set screw 10 having a cylindrical head fitting in this notch is screwed into the head of the temple and holds the blade 7 firmly in place. The corner 11 of this blade forms its cutting edge.

The cutting mechanism further comprises a movable cutter member which is preferably of the general construction shown in the Stimpson patent above referred to.

This cutter member has a rocking backward and forward movement in the usual vertical recess in the temple head. In the preferred construction illustrated it is a single integral cast iron casting. It comprises a body portion 12 of generally rectangular shape, a depending heel 13 and a cutter blade 14. The portion of the movable cutter member which forms the cutter blade 14 is chilled during the operation of casting and is thus hardened so that it may be ground off to present the required cutting edge 15.

Thus the entire member is cheaply and expeditiously formed as a single casting while the cutter blade portion is of the required hardness to provide the required cutting edge. In the construction illustrated the effective end of the integral cutter blade 14 is also formed at a slight angle with respect to the vertical plane of the body 12 so that when the movable cutter member is in position the cutter blade 14 diverges upwardly slightly away from the plane of the stationary cutter member.

This brings the cutting edge 15 close against the stationary vertical cutter member 7 and hence if the movable cutter member be held snugly against the fixed cutter member then an accurate and close co-operation of the two edges is assured during the cutting stroke.

In this invention the required pressure of the movable cutter member against the stationary cutter member is secured by a novel construction. A metal plate 16 of a shape

and construction generally similar to the stationary cutter member 7 is mounted in the temple head at the side of the movable cutter member opposite the stationary cutter member. This plate 16 is notched at 17 so as to fit over the cylindrical head of the set screw 10 but it is not locked by the set screw and hence the plate 16 is free to swing laterally to a slight extent at its upper end on the head of the set screw. A spring 18, preferably of helical form, is mounted in the temple head, preferably in a bore provided for that purpose, and abuts against the metal plate 16 below the axis about which the metal plate swings on the set screw 10. At its outer end this spring abuts against a base plate 19, shown as a flat strip of metal. This base plate is adjustably secured by a screw 20 to the outside face of the temple head.

It will thus be seen that by screwing the screw 20 into and out of the temple head the base plate 19 at its free end may be moved toward and from the temple head thus to vary the tension of the spring 18 and cause it to press against the metal plate 16. Thus the spring, with the required degree of tension, acts yieldingly to force the metal plate 16 against the movable cutter member 14 and thereby to force the cutting edge 15 of the movable cutter member into engagement with the cutting edge 11 of the stationary cutter member 7 during the cutting stroke.

There is thus provided a very simple, effective and accurate means for ensuring the engagement of the cutting edges of the cutter members during the cutting stroke under all conditions.

The movable cutter member is yieldingly held in place in the recess in the temple head in the usual manner as by the usual spring 21 coiled at one end about a stud 22 projecting from the bar 1 and at the other end about a stud 23 projecting from the side of the heel 13, this spring acting normally to hold the movable cutter member projected rearwardly with the cutting blade end elevated and with its cutting edge at the rear of the cutting edge of the stationary blade.

When the heel 13 is struck by the lay the movable cutter member is swung downwardly and projected forwardly to effect the shearing action between the cutting

edges of the two blades to sever the thread or filling end extending from the cloth.

55

Having thus described the invention what is claimed as new and desired to be secured by Letters Patent is:

1. A thread cutting temple for looms comprising a vertical stationary cutter member mounted in the temple head, a backwardly and forwardly movable cutter member co-operating with the stationary cutter member to sever the thread, a metal plate mounted in the temple head to swing laterally at its upper end and engaging the movable cutter member at the side opposite the stationary cutter member, and a spring mounted in the temple head and engaging the metal plate below the axis about which it swings and acting yieldingly to force the metal plate against the movable cutter member and thereby to force the cutting edge of the movable cutter member into engagement with the edge of the stationary cutter member during the cutting stroke.

75

2. A thread cutting temple for looms comprising the construction defined in claim 1 together with means for adjusting the tension of the spring.

80

3. A thread cutting temple for looms comprising a vertical stationary cutter member mounted in the temple head, a backwardly and forwardly movable cutter member co-operating with the stationary cutter member to sever the thread, a metal plate mounted in the temple head to swing laterally at its upper end and engaging the movable cutter member at the side opposite the stationary cutter member, a base plate mounted on the temple head, a helical spring abutting at one end the base plate and at the other end the metal plate below the axis about which it swings and acting yieldingly to force the metal plate against the movable cutter member and thereby to force the cutting edge of the movable cutter member into engagement with the edge of the stationary cutter member during the cutting stroke, and means for adjusting the base plate toward and from the metal plate thereby to adjust the tension of the spring.
